UNITED STATES PATENT OFFICE

170,396

POTENTIOMETER

Marlan E. Bourns, Riverside, Calif.

Application March 4, 1953, Serial No. 24,840

Term of patent 14 years

(Cl. D52—1)

To all whom it may concern:

Be it known that I, Marlan E. Bourns, a citizen of the United States of America, residing at Riverside, in the county of Riverside and State of California, have invented a new, original, and ornamental Design for a Potentiometer, of which the following is a specification, reference being had to the accompanying drawing, forming a part hereof:

Figure 1 is a perspective view of a potentiometer, showing my new design;

Figure 2 is a plan view showing the top of this device;

Figure 3 is a side elevation;

Figure 4 is a bottom plan view showing the underneath side of this device; and

Figure 5 is an end view of the same.

I claim:

The ornamental design for a potentiometer, substantially as shown.

MARLAN E. BOURNS.
